CLAIM

The ornamental design for a power and data receptacle mount, as shown and described.

DESCRIPTION

FIG. 1 is a top front perspective view of a power and data receptacle mount showing our new design;

FIG. 2 is a front elevation thereof;

FIG. 3 is a rear elevation thereof;

FIG. 4 is a top plan view thereof;

FIG. 5 is a bottom plan view thereof;

FIG. 6 is a right side elevation thereof; and,

FIG. 7 is a left side elevation thereof.

The dash-dash broken lines in the drawings are for the purpose of illustrating both environmental structure and portions of the article that form no part of the claimed design. The dot-dash broken lines in the drawings are for the purpose of illustrating the boundaries of the claim and form no part of the claimed design.

1 Claim, 2 Drawing Sheets
